(57) **CLAIM**

The ornamental design for an anchor point for a driver, as shown and described.

DESCRIPTION

FIG. 1 is a perspective view of an anchor point for a driver showing our new design;

FIG. 2 is another perspective view thereof;

FIG. 3 is a top plan view of the left side thereof;

FIG. 4 is a bottom plan view of the left side thereof;

FIG. 5 is a right side elevation view thereof;

FIG. 6 is a left side elevation view thereof;

FIG. 7 is a top plan view of the right side thereof;

FIG. 8 is a bottom plan view of the right side thereof; and,

FIG. 9 is a perspective view thereof attached to a driver. The broken lines shown in the figures illustrate structures for illustrative purposes only and form no part of the claimed design.
